UNITED STATES PATENT OFFICE

108,925

DESIGN FOR A COIN RACK

Nels H. Swanson, Chicago, Ill.

Application July 14, 1937, Serial No. 70,427

Term of patent 14 years

To all whom it may concern:

Be it known that I, Nels H. Swanson, a citizen of the United States, residing in the city of Chicago, in the county of Cook and State of Illinois, have invented a new, original, and ornamental Design for a Coin Rack, of which the following is a specification, reference being had to the accompanying drawing forming a part thereof.

In the drawing:

Figure 1 is a front view of a coin rack embodying my new design.

Figure 2 is a section taken substantially as indicated at line 2—2 on Figure 1.

Figure 3 is a top view of the device.

I claim:

The ornamental design for a coin rack substantially as shown.

NELS H. SWANSON.
